UNITED STATES PATENT OFFICE.

AMBROSE McVEY, OF WILMINGTON, DELAWARE.

SWITCH-SHIFTER.

1,154,526.

Specification of Letters Patent. Patented Sept. 21, 1915.

Application filed August 24, 1914. Serial No. 858,403.

To all whom it may concern:

Be it known that I, AMBROSE McVEY, a citizen of the United States, and a resident of Wilmington, in the county of New Castle and State of Delaware, have invented certain new and useful Improvements in Switch-Shifters, of which the following is a specification.

My invention relates to means for switching street railway cars, and the main object thereof is to provide a device which will accomplish this result from the front platform of a car and be under the control of the motorman.

15 A further object is to provide such a device which is normally out of operative position, but which may be placed in operative position by the motorman's foot.

20 A further object is to provide a foot pedal whereby the motorman may, at will, throw a switch to the right or to the left; and further objects are to provide such devices which are simple in construction and use, readily installed, composed of few parts not 25 likely to get out of order to require repair, and comparatively inexpensive.

25 My invention is fully described in the following specification, of which the accompanying drawings form a part, in which 30 like reference characters are used to designate like parts in each of the views, and in which:—

Figure 1 is a side elevation of the front platform of a surface car provided with my 25 invention, partly in section, and also showing the track apparatus; Fig. 2 is a plan view, taken on the line 2—2 of Fig. 1, of the mechanism for one rail of a railway; Fig. 3 is an enlarged view, in plan, of the track 40 apparatus, with the covers removed; and Fig. 4 is a section taken on the line 4—4 of Fig. 3.

In the drawings forming a part of this 45 application I have shown a present preferred form of embodiment of my invention, comprising a section of a car 5 having a platform 6 for the motorman, the car apparatus 7, and the track apparatus 8 and 9.

Slidably mounted in suitable hangers beneath 50 the platform 6 is a transverse shaft 10 upon which is secured a frame 11 carrying counterweights 12, a spring 13 for maintaining the same in approximately horizontal position, a foot pedal 14 for depressing 55 the same, and a roller 15 at the lower, forward, end thereof. Pivoted beneath the

platform 6, at 16, is a lever 17 which carries a foot pedal 18 at the forward end thereof operable in a slot 19 in said platform, and the rear end of which is pivotally connected 60 with a pin 20 secured on the shaft 10, movement of said pedal 18 in either direction sliding the said shaft and frame in a corresponding direction.

In Figs. 1 and 2 I have shown a guide 65 rail 21 arranged between the railway rails, preferably centrally thereof, which is branched by means of a central partition 22 into two passages 23 and 24, the floor of the guide rail being depressed in the positions 70 of said passages, as shown at 25, Fig. 1, and in each of these depressions is a dog 26 and 27, respectively, pivoted on a rod 28 in a box or housing 29 buried below the surface of the railway, each dog carrying 75 an arm 30 and 31, respectively, in turn connected, pivotally, with corresponding rods 32 and 33 which are forwardly extended through a conduit 34 into a casing 35 and pivotally connected with corresponding bell- 80 crank levers 36 and 37 in turn pivoted at 38 and 39, respectively, within the casing 35. Pivoted at 40, in said casing 35, between the pivots 38 and 39, is a lever 41 provided with oppositely directed arms 42 and 43, 85 and with a forwardly directed, slotted, portion 44 having a pin 45 slidable therein and carried by a rod 46 in pivotal connection with the switch 47 of the rails 48, only one rail with its branch and switch being illustrated, although the arrangement shown 90 may be duplicated at the opposite side of the railway at any point for switching the car to the left instead of to the right as illustrated. As the car approaches a switch, 95 the guide rail 21 being provided for a predetermined distance before a switch is reached, the motorman depresses the pedal 14 whereby the roller 15 bears on the guide rail 21 assuming that he does not want to 100 take the switch but go right along on the main track, he then forces the pedal 16 to the right which has the effect of moving the roller 15 to the left to enter the passage 23, and in which passage he strikes the dog 26 which, being forced downwardly by the roller 15, moves the bell-crank 36 rearwardly and inwardly, thereby striking the arm 42 of the lever 41 and forcing this lever 105 to the right, and, through the medium of the rod 46, also moving the switch 47 to the right, and the main line is open. Had

2
the parts been in this position, the motor-man would have continued on without touching the pedals referred to, unless he desired to take the switch, in which event 5 the foregoing operation would have been performed, with the difference, however, that he would have slid the frame 11 and roller 15 to the right, and this would have 10 actuated the dog 27 and bell-crank 37 to throw the lever 41 and switch to the left, and the car would then leave the main line. It will thus be seen that the switching of a car is directly under the control of the motorman and, while I have illustrated but one 15 switch, it will be obvious that the same apparatus may be applied to any number of switches, and on either side of the car, and the car apparatus is only actuated when the motorman sees that the switch is not properly set.

While I have shown certain structural details, it will be evident that I am not limited thereto, but may make changes thereover, within the scope of the following 25 claims, without departing from the spirit of my invention, or sacrificing its advantages.

Having fully described my invention, what I claim as new, and desire to secure by 30 Letters Patent, is:—

1. A switch operating device, comprising a pivoted switch, a lever connected thereto, a bell-crank lever on each side of said lever adapted to bear on the respective side thereof, a tripping dog in operative connection with each bell-crank lever, said

switch and lever being movable independently of said bell-crank levers, and means carried by a car for tripping either of said dogs to correspondingly move said switch. 40

2. A switch operating device, comprising a pivoted switch, a lever connected thereto, a bell-crank lever on each side of said lever adapted to bear on the respective side thereof, said lever being movable independently of said bell-crank levers, a tripping dog in operative connection with each bell-crank lever, means for maintaining said bell-crank and dogs in normal positions, and means carried by a car for tripping either of said dogs to correspondingly move 45 said switch. 50

3. A switch operating device, comprising a pivoted switch, a lever connected thereto, a bell-crank lever on each side of said lever adapted to bear on the respective side thereof, a tripping dog in operative connection with each bell-crank lever, said switch being movable independently of said bell-crank levers, means carried by a car 60 for tripping either of said dogs to correspondingly move said switch, and means for guiding said tripping means to the respective dogs. 65

In testimony whereof I have signed my name to this specification in the presence of two subscribing witnesses.

AMBROSE McVEY.
